UNITED STATES PATENT OFFICE

CHARLES B. GILMORE, OF CHICAGO, ILLINOIS

CONTROL MECHANISM

Application filed August 23, 1928. Serial No. 301,519.

My invention relates to controlling means for starting apparatus.

One of the objects of my invention is to provide improved means for preventing the 5 operation of the motor starter of a motor vehicle while the clutch is in connecting position.

A further object is to provide an improved 10 construction, which will under ordinary circumstances prevent the motor starter from being operative while the motor is connected with the propulsion, but which will enable the starting apparatus to be operative under certain conditions to cause propulsion of the 15 vehicle.

Further objects will appear from the description and claims.

In the drawings, in which two embodiments 20 of my invention are shown,

Figure 1 is a diagrammatic view showing clutch control starter apparatus;

Fig. 2 is a view similar to Fig. 1 showing the clutch and starter button depressed;

Fig. 3 is a view similar to Figs. 1 and 2 25 but showing the starter button still depressed but with the clutch pedal in connecting position;

Fig. 4 is a view similar to Fig. 1 but showing a different form of my invention.

Referring to the drawings in detail, and first to Figs. 1, 2 and 3, the construction shown therein comprises the internal combustion engine 1 of an automobile, a starter motor 2 for the gas engine, a clutch pedal 3 for controlling the connection of the engine with the propulsion, a starter button 4 for controlling the starter motor, and a floor board 5, seat 6, steering wheel 7 and dash 8 of the automobile. These parts may be of any usual 40 or suitable construction. The construction shown further comprises means whereby the starter button 4 is normally held against being depressed so long as the clutch pedal 3 is raised in position to connect the engine with the propulsion.

The means shown for this purpose comprise a blocking slide 9 slidably mounted in a bracket 10 secured to the floor board 5. A 50 coil tension spring 11 tending to hold this slide in rearward position to block the depre-

sion of the starter button and link 12 pivotally connected with the front end of the slide 9 and having a lost motion connection 13 with the clutch pedal. This lost motion connection permits the clutch to be operated sufficiently to connect and disconnect the engine from the propulsion without causing any movement of the slide 9, but enables the slide to be operated by an abnormal depression of the clutch pedal as shown in Fig. 2 to withdraw the blocking slide 9 from underneath the pin 14 on the starter button, thereby enabling the starter button to be depressed to put the starter motor in operation to start the gas engine. When the engine is running 65 the foot is taken off the starter button and the clutch can then be operated in the usual way.

The lost motion connection 13 between the slide 9 and clutch pedal 3 also enables another desirable result to be accomplished, to wit: That once the starter button has been depressed it may be held depressed by the foot and the clutch pedal still allowed to come back to connecting position as shown in Fig. 3 so that the starter motor may in any emergency be used to propel the vehicle. This is sometimes desirable in the event that the gas engine might fail to operate at a critical time and it should become necessary to use the starter motor as a means of propulsion. 80

It will be seen that the construction shown will ordinarily prevent the starter button from being depressed when the propulsion is connected with the engine. This is desirable as otherwise accidents are likely to happen due to putting the starter motor in operation while the propulsion is connected with the engine. It will also be seen that the construction enables the starter motor to propel the vehicle in case of emergency by holding the starter button depressed and allowing the clutch to come back into connecting position.

In Fig. 4 is shown a construction in which similar results are accomplished by means of a clutch controlled switch 15 in series with the switch controlled by the starter button 4. In this construction the clutch controlled switch pivotally mounted at 16 is connected with the clutch pedal 3 by means of a link 100

17 pivotally connected with the switch lever at 18 and having a lost motion connection 19 with the clutch pedal. With this construction in starting the motor ordinarily 5 simply depressing the starter button will not put the starter motor in operation as the circuit will not be completed until the clutch pedal is depressed closing the clutch controlled switch 15. The lost motion connection 10 enables the normal operation of the clutch pedal without causing operation of the pivoted switch blade. However, an abnormal operation of the clutch pedal will close the knife switch 15 and thereupon depressing the start- 15 er button will put the starter motor in operation. In case of an emergency arising in which it might be desirable to use the starter motor as a means of propulsion this may be accomplished by means of a switch 20 in parallel 20 with the clutch controlled switch 15. This emergency switch is normally held open by means of a coil tension spring 21 but may be closed by means of a pull rod 22 at the dash 8 connected with the emergency switch 20 by 25 means of a bell crank lever 23 and pull rod 24. A spring 25 is provided for normally holding the clutch controlled switch open. If desired means may be provided which will hold the emergency switch 21 closed, even if 30 the pull rod 24 is released, such as a stick magnet 26 which is energized so long as the starter motor circuit is closed and hence will hold the emergency switch closed so long as 35 the starter button is depressed. However, as soon as the starter button is released the starter motor circuit is opened and the stick magnet 26 will release the emergency switch, whereupon the spring 21 will throw this 40 emergency switch open.

40 The stationary switch contacts 27 and 28, which cooperate with the switch blades 15 and 20 respectively, are both electrically connected with the starter motor 2 through a conductor 29. The stick magnet 26 is connected with ground 30.

45 This construction also normally prevents putting the starter motor into operation when the engine is connected with the propulsion but nevertheless enables the starter 50 motor to be used as a means of propulsion in case of emergency.

55 While I have shown but two embodiments of my invention, it is obvious that it may be embodied in other forms covered and defined by the appended claims.

I claim:

1. An automobile construction comprising means for connecting and disconnecting the engine with respect to the propulsion, means 60 operable by the driver for starting the starter motor, means whereby when said connecting and disconnecting means are initially in connecting position said driver operable means are inoperative to start the starter motor, and 65 means whereby said driver operable means

may be made operative to maintain the start- 70 er motor in operation regardless of whether or not the connecting or disconnecting means are in connecting position.

2. A motor vehicle construction comprising 75 means for connecting and disconnecting the motor with respect to the propulsion, means operable by the driver for starting the motor, means whereby when said connecting and disconnecting means are initially in connecting position said driver operable means are inoperative to start the motor, and means 80 whereby said driver operable means may be made operative to start the motor regardless of whether or not the connecting and disconnecting means are in connecting position.

3. A motor driven vehicle comprising a 85 motor, a motor starter, power transmission means connectible and disconnectible by the foot of the driver, means for rendering the starter inoperative while said power transmission is connected, and means whereby the transmission may be connected while said starter is in effective operation.

4. A motor vehicle comprising a motor, a 90 motor starter, connectible and disconnectible power transmitting means, means for rendering said motor starter inoperative while said transmission is connected, whereby the transmission means may be connected during the 95 effective operation of said starter.

In witness whereof, I have hereunto sub- 100
scribed my name.

CERTIFICATE OF CORRECTION.

Patent No. 1,841,285.

Granted January 12, 1932, to

CHARLES B. GILMORE.

It is hereby certified that error appears in the printed specification of the above numbered patent requiring correction as follows: Page 2, line 15, for the misspelled word "pue" read put; same page, line 88, claim 3, after "transmission" insert the word means, and line 94, claim 4, before "whereby" insert the words and means; and that the said Letters Patent should be read with these corrections therein that the same may conform to the record of the case in the Patent Office.

Signed and sealed this 1st day of March, A. D. 1932.

(Seal)

**M. J. Moore,
Acting Commissioner of Patents.**
